STACY B. HASELTINE, OF CHICAGO, ILLINOIS, ASSIGNOR TO W. H. MINER, INC., OF CHICAGO, ILLINOIS, A CORPORATION OF DELAWARE

SHOCK-ABSORBING MECHANISM ESPECIALLY ADAPTED FOR DRAFT RIGGING OF RAILWAY CARS

Application filed January 28, 1928. Serial No. 250,136.

This invention relates to improvements in shock absorbing mechanisms especially adapted for draft riggings of railway cars.

One object of the invention is to provide a shock absorbing mechanism especially designed for railway draft riggings, of simple construction and rugged design, having a relatively long stroke in buff to take care of the heavy buffing shocks, and a comparatively shorter stroke in draft.

Another object of the invention is to provide a shock absorbing mechanism of the character indicated, having relatively light initial action in buff, followed by heavier action during the remainder of the buffing stroke, and affording relatively light resistance during the draft action wherein the stroke of the mechanism is relatively shorter in draft than in buff.

20 A further object of the invention is to provide a shock absorbing mechanism, including spring shock absorbing means actuated in both buff and draft, and additional high resistance friction shock absorbing mechanism, operative in buff only, to absorb the heavier shocks.

Yet another object of the invention is to provide a shock absorbing mechanism, including relatively light resistance mechanism 30 operated directly through the usual coupler member in buff, and through yoke means in draft, and friction shock absorbing mechanism operated in buff only, wherein the yoke means is so arranged as to transmit the force 35 directly to the shock absorbing mechanism in buff, and the forces are transmitted through the friction shock absorbing mechanism directly to the usual bolster of the car, the arrangement being such that the compression of the light resistance mechanism in buff 40 is limited and the forces are transmitted through column-acting means from the coupler means to the friction shock absorbing mechanism.

45 Other and further objects of the invention will more clearly appear from the description and claims hereinafter following.

In the drawings, forming a part of this specification, Figure 1 is a vertical, longitudinal, sectional view, corresponding to the cen-

ter line of the car, showing my improvements in connection therewith. Figure 2 is a horizontal, longitudinal, sectional view, corresponding substantially to the line 2-2 of Figure 1.

In said drawings, 10-10 indicate the usual channel-shaped center sills of a railway car underframe. The angle end sill of the car is designated by 11 and the end wall sheathing by 12. As clearly shown in Figure 1, the end wall sheathing has a section thereof disposed horizontally and extending to the floor plate or cover plate 13, which overlies the center sills. The buffer block is indicated by 14 and may be of any well known form. As herein shown, the buffer block comprises a casting having an upstanding portion abutting the front face of the angle end sill 11 and a horizontal top wall extending rearwardly and below the horizontal section of the angle end sill 11. The buffer block is secured to the end sills 11 in any well known manner. The buffer block is provided with inwardly projecting flanges 15 at the top and sides, which function as limiting stops for the yoke member hereinafter described. The buffer block supports the usual carry iron, designated by 16, which may be formed as a separate member or may be formed integral with the buffer block casting. The usual body bolster 20 is indicated by 17 and has a bolster filler casting 18 associated therewith, the casting 18 being disposed between the sills 10 and functioning as a rear stop member, which cooperates with the shock absorbing mechanism.

In carrying out my invention, the center sills 10 are provided with suitable slots 19-19 at the outer ends thereof, adapted to receive the coupler key. The sills are also provided with stop castings 20-20, secured to the inner sides thereof, the stop castings being provided with longitudinal slots aligned with and forming continuations of the slots 19 of the sills. As shown, the castings 20 are in the form of elongated heavy plates, having their front ends abutting transverse walls 21-21 of the buffer block 14. At the rear ends, the plates present vertical shoulders 22-22, which act as limiting stops. Between the 100

ends thereof, the castings 20 have inwardly projecting enlargements 23, presenting rear shoulders 24, which function as stop elements.

My improved railway draft rigging includes broadly a friction shock absorbing mechanism A; a yoke member B; spring shock absorbing means C; a main follower D; an auxiliary follower E; a coupler F; and a coupler key G.

10 The shock absorbing mechanism A, which preferably includes friction elements, as shown in Figures 1 and 2 of the drawings, is of the usual type, comprising a friction shell having interior friction surfaces and 15 friction means co-operating with said surfaces, including friction shoes and a wedge member resisted by the usual spring means. The friction shoes as shown, are two in number and are designated by 25-25, and have 20 the wedge member 26 co-operating therewith. The inner end of the friction shell of the shock absorbing mechanism A bears directly on the rear stop casting 18, and the wedge member 26 co-operates with the follower E, 25 which is in the form of a heavy rectangular plate. The follower E normally engages the inner ends of the castings 20 and is held against outward movement by the stop shoulders or faces 22 of said castings. It will be 30 evident that the outward movement of the follower E being limited, the expanding action of the friction shock absorbing mechanism A is positively limited thereby. It is further pointed out that inasmuch as the 35 usual friction shock absorbing mechanism includes a retainer bolt which holds the parts assembled and limits the outward movement of the wedge member with respect to the other parts of the mechanism, the expanding 40 action of the shock absorbing mechanism A will be limited independently of the employment of the follower E.

The coupler F is of standard design and comprises the usual coupler head and shank 45 27 rearwardly extending therefrom. As shown, the shank 27 is tapered rearwardly from the coupler head, the inner extremity of the shank having the opposite side walls thereof disposed substantially parallel. The 50 coupler shank 27 bears directly on the main front follower D, which has its outward movement limited by engagement with the stop shoulders 24 of the castings 20.

The yoke B is in the form of a substantially tubular sleeve member, having horizontally disposed top and bottom walls 28 and 29, longitudinally extending short side walls 30-30 at the rear end thereof, a transverse rear end wall 31, and inwardly converging 60 short side walls 32-32 at the forward end thereof. As most clearly shown in Figure 2 of the drawings, the walls 32 at the forward end of the yoke member have the front portions thereof disposed substantially parallel, 65 the inner faces of said walls converging rear-

wardly of the mechanism. The converging relation of the inner faces of the walls 32 permits the necessary lateral displacement of the coupler in the the operation of railway cars when on curved track. As shown in Figure 70 1, the bottom wall of the yoke extends a substantial distance beyond the top and side walls thereof, and forms a supporting ledge for the shank of the coupler adjacent the coupler head or horn. The shank of the coupler F is anchored to the yoke by means of a transverse coupler key G which works in the longitudinal openings or slots 19 of the sills 10, the key G being of the headed type and having means at the opposite end to the head 75 for preventing removal of the same. Any suitable means may be employed for this purpose, the usual retainer pin with cotter being illustrated in Figure 2 of the drawings. As shown in the drawings, the walls 32 of the yoke are slotted at the inner ends thereof to accommodate the coupler key G, and the front end walls of these slots, which are indicated by 80 33, form limiting stops for the key G, whereby the yoke B will be compelled to move 85 outwardly in unison with the key and the coupler F during a draft action. As most clearly disclosed in Figure 2, the side walls 30 at the inner end of the yoke, have their forward ends spaced from the inner face of the 90 main follower D, thereby permitting a certain amount of relative movement between the yoke and the follower D before outward movement of the yoke is arrested by engagement with said follower, or inward movement of the yoke is effected by engagement of the follower with the front ends of the side walls 30. The castings 20, in addition to 95 acting as stops, also form guides for the yoke in its movement lengthwise of the draft rigging. The height of the coupler shank is such as to substantially fit between top and bottom walls 28 and 29 of the yoke, and the coupler key G is fitted to the slots 19 and the 100 opening in the coupler shank, so that the latter will be held against vertical displacement with respect to the yoke and sills. It will be clear that inasmuch as the coupler shank and yoke are maintained against relative vertical displacement, and further that the bottom 105 wall of the yoke supports the coupler shank closely adjacent the head of said coupler, the weight of the coupler head and adjacent section of the shank will be substantially overbalanced by the yoke and the other parts 110 therewithin and the rear portion of the coupler shank, thereby preventing tilting or rocking of the coupler shank with resultant wear of the parts carrying the same. It will 115 further be evident that only limited movement of the coupler with respect to the yoke is provided, the same being equal to the relative movement permitted between the main follower D and the yoke. In addition to housing the main follower D, the yoke also houses 120 125 130

the shock absorbing spring C, which is shown in the form of a single coil, although it will be evident that more than one coil may be employed if desired. The coil spring C is disposed within the pocket formed by the top, bottom, side and end walls of the yoke, and has its opposite ends bearing on the end wall 31 and the main follower D respectively. The spring C is preferably placed under a substantial amount of initial compression, so that it will offer the desired amount of resistance at the beginning of the compression stroke.

The shell of the friction shock absorbing mechanism and the yoke member, may be supported by any suitable means, but as herein shown they are preferably supported by carry plates 34 secured to the center sills. An additional guide plate 35, substantially secured to the cover plate 13, prevents upward displacement of the yoke B, follower D and shock absorbing mechanism A.

The operation of my improved shock absorbing mechanism, assuming a buffing action being applied to the coupler, is as follows: The coupler will be forced inwardly and the coupler shank 27, which is in engagement with the follower D, will force the follower D rearwardly with respect to the yoke B, thereby compressing the spring resistance C. During this action, the inward movement of the yoke will be resisted to a great extent by the friction shock absorbing mechanism A, which is of greater capacity than the shock absorbing mechanism comprising

the spring C, but, as will be evident, the friction shock absorbing mechanism will be compressed to some extent during this action. The inward movement of the follower D, with respect to the yoke, will continue until the follower engages the front ends of the side walls 30 of the yoke, whereupon the yoke will be forced rearwardly in unison with the coupler, carrying the follower E therewith, and further compressing the friction shock absorbing mechanism A without additional compression of the spring C. During the buffing action, there is thus provided a relatively light spring resistance at the initiation of the buffing stroke, followed by a much heavier resistance during the operation of the friction shock absorbing mechanism. It is further pointed out that the total buffing stroke of the coupler is equal to the combined compression of the spring resistance

shock absorbing mechanism C and the friction shock absorbing mechanism A. The parts are so proportioned that the total amount of movement in buff will be about five and one-half inches. Although a stroke of five and one-half inches has been illustrated in the drawings, it will be appreciated that the invention is not limited thereto and that the stroke may be varied within wide limits. The buffing action as described, will continue either until the actuating force is

reduced or the inward movement of the coupler is positively limited by the front follower D engaging the limiting shoulders on the yoke B, and the follower E engaging the front end of the friction shell of the friction shock absorbing mechanism A, the latter being held against rearward movement by the stop casting 18. When the parts have reached the compression stage last described, the actuating force is transmitted directly through the solid walls of the yoke member, the followers and the casing of the friction shock absorbing mechanism, to the draft sills, thereby preventing the spring resistance C of the spring shock absorbing mechanism and the spring resistance of the friction shock absorbing mechanism from being unduly compressed. Upon the actuating force being sufficiently reduced, the expansive action of the spring resistance means of the friction shock absorbing mechanism will force the follower E outwardly until limited by engagement with the inner ends of the castings 20. During the outward movement of the follower E, the yoke will be forced outwardly also, and the expanding action of the spring C will force the follower D forwardly with respect to the yoke, outward movement of the follower D being finally limited by engagement with the stop shoulders 24 of the castings 20.

During a draft action, the coupler F will be pulled outwardly, carrying the yoke B therewith, the coupler key G, which engages the shoulders 33 on the side walls 32 of the yoke, compelling the forward or outward movement of the yoke. Inasmuch as the follower D is held stationary by engagement with the stop shoulders 24 on the castings 20, the spring resistance C will be compressed between the end wall 31 of the yoke and the follower D, until the front ends of the side walls 30 of the yoke engage the follower D, and the front ends of the yoke engage the stops formed by the flanges 15 on the buffer block, thus positively arresting movement of the yoke. As herein illustrated, the amount of movement permitted between the yoke and the follower D during compression of the spring C, is preferably one and one-half inches, thus providing a much shorter stroke of the mechanism in draft than in buff. Although the movement as shown is one and one-half inches, it will be evident that the invention is not limited to this amount of movement and that the same may be varied within wide limits as long as the movement in draft is less than the movement in buff.

While I have herein shown and described what I consider the preferred manner of carrying out the invention, the same is merely illustrative, and I contemplate all changes and modifications which come within the scope of the claims appended hereto.

I claim:

1. In a railway draft rigging, in combination: draft sills; a buffer casting at the outer ends of said sills; shock absorbing means; a hooded vertical yoke; a standard coupler; a key connecting the yoke and coupler, said sills, yoke and coupler having horizontally aligned slots for the reception of the key, the distance between the front edges of said slots in the sills and a vertical plane passing through the striking face of the buffer casting being less than the distance between said striking face and the striking face of the horn of the standard coupler when the latter is in full release position; and means extended forwardly of the front edges of said sill slots for supporting the shank and outer end of the coupler.

2. In a draft rigging, in combination: parallel draft sills; shock absorbing means; a standard type D coupler; a coupler key; and a single-piece yoke, said yoke having a vertical loop section, a hood section with laterally flared side walls and a bottom coupler-supporting wall, all formed integrally, said bottom wall being extended outwardly beyond the coupler key slot and of such width as to always provide a full bearing support for the coupler shank in any laterally adjusted position of the coupler, said coupler being endwise insertible within and removable from said hood section of the yoke.

In witness that I claim the foregoing I have hereunto subscribed my name this 17th day of January, 1928.

STACY B. HASELTINE.
